UNITED STATES PATENT OFFICE.

CHARLES V. ROTE, OF LANCASTER, PENNSYLVANIA, ASSIGNOR OF ONE-HALF TO E. W. BROWN, OF LANCASTER, PENNSYLVANIA.

FULL MECHANISM FOR RAILWAY CARS.

Application filed July 27, 1920. Serial No. 399,307.

To all whom it may concern:

Be it known that I, CHARLES V. ROTE, a citizen of the United States, residing at Lancaster, in the county of Lancaster and ⁶⁰ State of Pennsylvania, have invented new and useful Improvements in Pull Mechanisms for Railway Cars, of which the following is a specification.

The present invention relates to improvements in pull mechanisms for railway cars and has for its object to provide means by which a train of cars may be started more smoothly and with less jar, than can be done with the draft devices commonly employed.

According to the present invention means are provided whereby a pull or draft exerted on the coupler at the front end of the forward car of a train will be immediately transferred to the second car. By this arrangement when starting a train the pull or draft exerted by the engine on the forward car will be transmitted, first, to the car immediately in rear of the car to which ⁷⁵ the coupler receiving the initial pull is attached so that the second car will be started first.

In the accompanying drawings two embodiments of the invention are illustrated, ³⁰ the several views being largely diagrammatic and omitting a number of parts which are in common use in railway draft appliances.

In the drawings:—

Figure 1^a is a plan view of one end of a railway car, having an embodiment of the invention applied thereto;

Figure 1^b is a similar view of the other end portion of the car;

Figures 2^a and 2^b are, respectively, side elevations of parts shown in Figures 1^a and 1^b;

Figure 3 is a transverse sectional view substantially on the line 3—3 of Figure 2^a;

Figure 4 is a view substantially on the line 4—4 of Figure 1^b, on an enlarged scale;

Figure 5 is a plan of a portion of another embodiment of the invention;

Figure 6 is a side elevation of parts shown in Figure 5;

Figure 7 is a sectional view substantially on the line 7—7 of Figure 5, on an enlarged scale.

In the drawings the frame of the car is diagrammatically illustrated as comprising

longitudinal side members 1, 1', end sills 2, 2', and a series of transversely extending frame beams 3, 3'. The embodiments of the invention selected for purposes of illustration are both applied to a car which is provided with a centrally arranged longitudinally extending box girder comprising angle irons 4, 4', that extend throughout the length of the car and are connected by a top plate or member 5, which for clearness of illustration of other parts, hereinafter referred to, is removed in all of the figures except Figure 3.

The side members 4, 4', of the central girder of the car frame are shown as being of greater height or depth along the mid section of the car than at the ends thereof and within the channels formed on the outer surfaces of said members are arranged the pull bars that will be hereinafter more particularly described.

Referring particularly to Figures 1^a to 4 inclusive, 6, 6', designate the draft couplers of the car, which may be of any suitable type and are attached, in the ordinary manner, to draw bars 7, 7', which extend through suitable guides on the end frame members 2, 2'. With said draw bar cooperates a yielding or spring mechanism such as commonly used and which is conventionally illustrated at 8, in Figure 2^a.

Each of the couplers, 6, 6', is connected with a set of draft appliances which are interconnected so that there may be a relative movement between them in the direction of the length of the car. In the embodiment of the invention shown in Figures 1^a to 4, each set of draft appliances includes two longitudinally extending bars 9, 9', which are arranged on opposite sides of the central longitudinal girder, in the channels formed thereby, and transverse members 10, 10'. The members 10, 10', extend through suitable slots formed in the walls 4, 4', of the frame girder and said members and the draft bars are connected by means permitting relative movement in the direction of the length of the car. As shown, the draft bars are provided with longitudinal slots 11, 11', into which extend pins 12, 12', attached, respectively, to the transverse members 10, 10'.

The couplers, 6, 6', are respectively connected by reach rods 13, 13', with bars 14, 14', that extend through suitable slots in

the girder walls 4. As shown, the rods 13, 13', have loops or elongated eyes formed in the ends thereof remote from the couplers and through these extend pins or studs 15, 15', on the cross bars, 14, 14'.

Rods 16, 16', respectively, connect the pins or studs 15, 15', with levers 17, 17', which are fulcrumed at one end on bosses or plates 18, 18', that project laterally outward from the girder walls 4, 4', and are connected by links 19, 19', with toggles 20, 20'. One end of each of the toggles is connected with the adjacent transverse draft member 10, 10', being shown as connected to the pin or stud 15 which constitutes the connection between said transverse member and the longitudinal member, 9, 9', while the other end of the toggle has at its free end a pin or stud 22, 22', that extends through a slot 23, 23', in the longitudinal draft member 9, 9'.

Beyond the cross bars 14, 14', each longitudinal draft bar 9, 9', is provided with a pin or abutment 24, 24', and means are provided, whereby movement of the cross bars 14, 14', may be transmitted to said draft bars through said pins or abutments. In the embodiment of the invention illustrated in Figures 1^a to 4 this connecting means comprises a slide 26, 26', adapted to be reciprocated through openings in the walls of the car frame girder. One edge of each of said slides is parallel throughout its length with the adjacent cross bar 14, 14', while in the opposite edge are formed two recesses 25, 25'. The sides of said recesses 25, 25', are inclined or cam shape and when the slide is moved, in one direction the solid portions thereof will completely fill the space between the adjacent cross bars 14, 14', and the abutments or studs 24, 24', on the draft bars 9, 9'.

For moving each of said slides levers 27, 27', are fulcrumed on the bars 14, 14', and the short arm of each thereof extends into a slot or opening in the adjacent slide. Movement of the levers 27, 27', is normally limited by pins 28, 28', extending upward from levers 29, 29', which are fulcrumed on brackets 30', projecting from the central girder of the car frame, and normally extend upward into the path of the levers 27, 27'. In order to permit the slides to be shifted from either side of the car, members of each pair of the levers 29, 29', are connected at their inner ends, as shown in Figure 3, so that movement of either lever to withdraw its pin 28, from the path of movement of the lever 27, 27' will be transmitted to effect a corresponding movement of the other lever and its stop pin.

The two sets of draft members, 9, 10, and 9', 10', are connected by links 30, which extend from the pins or studs 12, to the pins or studs 12', so that when either bar 10, 10', is moved a corresponding movement will be

directly transmitted to the other of said bars.

The operation of the embodiment of the invention hereinbefore described may be briefly stated as follows:

The parts being in the relative positions shown in Figures 1^a to 2^b a pull upon the coupler 6 will be transmitted to the cross bar 14, through the links 13 and such bar will be moved in the slots in the frame girder toward the left in Figure 1^a. This movement will not be directly transmitted to the bars 9 because the notches 25 of the slide 26 are opposite the pins 24 and the slide can move with the bar 14 without directly moving the bars 9. The pull exerted on the rods 16 by such movement of the cross bar 14 will operate to expand the toggle 20 and move the cross bar 10 relative to the longitudinal draft bars 9, the connections 12 moving in the slots 11. As the bars 10, 10', are directly connected by the links 30 such movement will be immediately transferred to the bar 10'. The connections 12' being at the ends of the slots 11' toward the coupler 6, and the slide 26' being interposed between the cross bar 14' and the studs or abutments 24', movement of the bar 10' will be directly communicated to the bars 9, 9', and, through the rods 13' to the coupler 6', and thus to the next car which is coupled to the coupler 6'.

The second car will, therefore, be started before the first car and caused to exert a pushing action on the forward car. By this arrangement the coupling and yielding draft devices between the locomotive and first car will not be subjected to the direct sudden pull which so frequently, in starting trains, acts to disconnect them from the car.

It will be seen that as the parts are moved, as above described, in transmitting pull from the coupler 6 direct to the coupler 6' the toggles 20, 20' will be, respectively, expanded and contracted, and such operation will be reversed in case the parts are so adjusted that the initial pull will come upon the coupler 6'.

By interposing a toggle between each draft coupling and the transverse bar 10, 10' there is provided a draft rigging, the effective length of which is variable; and the parts are so proportioned that when two cars are coupled together the variation in the effective lengths of the draft riggings 120 will be such that the second car will be started in advance of the forward car to a coupler of which the draft is directly applied.

If it is desired to start the car in the opposite direction, the slides 26, 26', will be actuated to reverse the relations thereof to the bars 14, 14', from that illustrated when a pull on the coupler 6' will operate to expand the toggle 20' and exert a pull directly through the draft bars 9 to the coupler 6 at 130

the other end of the car, at the same time collapsing the toggle 20.

In Figures 5, 6 and 7 there is illustrated a slightly different arrangement of parts operating in the same manner as the embodiment of the invention hereinbefore described. Referring particularly to said Figures 5 to 7, inclusive, the coupler 6' is connected by rods or links 13' with transverse draft member 31' which, through rods 32' is connected with outwardly extending projections 33' on one member of a toggle 34'. The ends of the members of the toggle 34' are connected to transverse members 35', 36', the connection between the bar 35' and the toggle being provided by pins that extend through slots 37' in the bars 9'. Said bars are of such length that they overlap the bars 9 leading from the opposite end of the car, as in Figure 1^a.

It will be understood that the parts illustrated in Figures 5 and 6 and above described are duplicated at the other end of the car, the cross member 36 and a portion of the toggle 34 being only illustrated. The cross members 36, 36' extend through slots 40, 40' formed in the side walls of the central girder of the car frame.

In this embodiment of the invention the cross bar 31' is shown as made of angle iron and transversely across the space formed between its top and bottom members extend pins 42 against which the slide 26' bears. As in the embodiment of the invention first described the longitudinal bars 9' are provided at their free ends with pins 24' with which cooperate the notches 25' in the slide 26' as before described. The slide is reciprocated by levers 43, so that it will occupy either the position shown in Figure 5 or will extend continuously across the space between the pins 42, 24'.

The operation of the embodiment illustrated in Figures 5 to 7 being the same as that illustrated in Figures 1^a to 4 that has been described in detail is not repeated here.

It will be evident that the invention may be embodied in various forms of mechanism differing from those selected for purposes of illustration and that the accompanying illustrations are largely diagrammatic. It is not desired, therefore, to limit the invention, in its broader aspects, to the specific arrangements of parts that are shown in the drawings.

Having thus described the invention what is claimed and desired to be secured by Letters Patent is:

1. The combination with a railway car provided with a coupler at each end, of two sets of draft devices carried by the car and each comprising members extending respectively longitudinally and transversely of the

car and connected together by means permitting relative movement between them in the direction of the length of the car, such connection including a toggle having its members respectively connected with the transverse and longitudinal members of each said set, the connection between the toggles and longitudinal members permitting relative movement between them in the direction of the length of the car, each of said sets being movable as a unit longitudinally of the car, means connecting the toggle of each said set with the adjacent coupler, a rigid connection between the transverse members of the two sets, and adjustable means for preventing relative movement between the members of either of said sets longitudinally of the car.

2. The combination with a railway car frame, having a draft coupler at each end, of two toggles each having both members pivotally connected to the car frame, the connection between each of said members and the frame being movable in the direction of the length of the frame, a rigid connection between adjacent members of the toggles, a connection between each toggle and the adjacent coupler, and adjustable means for preventing relative movement between one of the members of each toggle and the frame.

3. The combination with a railway car frame, having a draft coupler at each end, of two toggles each having both members pivotally connected to the car frame, the connection between each of said members and the frame being movable in the direction of the length of the frame, a rigid connection between adjacent members of the toggles, a connection between each toggle and the adjacent coupler, and a slide adjustable transversely of the frame for preventing relative movement between one of the members of each toggle and the frame.

4. The combination with a railway car frame, having a draft coupler at each end, of two toggles each having both members pivotally connected to the car frame, the connection between each of said members and the frame being movable in the direction of the length of the frame, a rigid connection between adjacent members of the toggles, a connection between each toggle and the adjacent coupler, an adjustable device for preventing relative movement between one of the members of each toggle and the frame, and a plurality of levers projecting laterally from both sides of the frame, each lever being adapted to control operation of two of said devices, for the purpose described.

In testimony whereof I have hereunto set my hand.

CHARLES V. ROTE.
